UNITED STATES PATENT OFFICE

WILLIAM SCHWEMLEIN, OF PARKERSBURG, WEST VIRGINIA, ASSIGNOR TO THE PARKERSBURG RIG & REEL COMPANY, OF PARKERSBURG, WEST VIRGINIA, A CORPORATION OF WEST VIRGINIA

BRAKE DRUM

Application filed April 5, 1928. Serial No. 267,653.

This invention relates to brake or similar drums or wheels.

The present invention relates to a structure particularly adapted for use as a brake drum in connection with the sand reel shafts of well drilling apparatus.

In connection with such an apparatus, it is the present practice to provide a sand reel shaft having a spool thereon, and adapted to be driven from a suitable source of power through manually controlled clutch means. The shaft is provided with a brake drum adapted to be engaged by a suitable brake band. The spool mounted upon the sand reel shaft is engaged by a cable passing over a suitable sheave and connected to the apparatus employed in connection with the drilling operation, such as the baler. The clutch is engageable for rotating the sand reel shaft to elevate the baler, while the brake is operable to retard the lowering of the baler into the well.

The brake drum, in an apparatus of this character, is subjected to considerable friction, and in operation, the engaging surface of the drum becomes heated to temperatures as high as 700° F. The central portions of the drums remain relatively cool, and accordingly severe internal stresses are set up in the metal of the drum.

An object of the present invention is to provide a drum structure of the character referred to wherein means is provided for permitting the free expansion of the peripheral portions of the drum without affecting the inner portions thereof.

A further object is to provide a drum of the character referred to which comprises separate inner and outer portions connected in driving relationship whereby they rotate as a unit, the outer portion referred to being adapted to partake of expansion and contraction independently of the inner portion.

A further object is to provide novel connecting means between the inner and outer portions of the brake drum to permit differential expansion and contraction to take place between the two portions of the drum.

A further object is to provide novel means associated with the peripheral portion of the

drum for agitating air in the vicinity thereof to assist in radiating heat from such peripheral portion.

A further object is to provide a device of the character just referred to wherein the agitating means constitutes in itself means for assisting in the radiation of heat from the peripheral portion of the drum.

A further object is to provide a device of the character referred to wherein the air agitating means performs the further function of providing reinforcing means for the peripheral portion of the drum.

Other objects and advantages of the invention will become apparent during the course of the following description.

In the drawings I have shown one embodiment of the invention. In this showing,

Figure 1 is a side elevation, and,

Figure 2 is a section taken substantially on line 2—2 of Figure 1.

Referring to the drawings, the numerals 10 and 11 indicate respectively inner and outer sections forming in effect a single brake drum, as will be apparent. These sections include flange portions 12 and 13 respectively, arranged in radial alinement, as shown in Figure 2. The inner section further includes a hub 14 having a circular shaft receiving opening 15 therein. The hub also is provided with the usual key slot 16 by means of which the inner section 10 may be keyed to the shaft. The hub and flange of the inner section are connected by preferably integral ribs 17.

The outer section 11 is provided with a cylindrical peripheral portion 18 having its outer face adapted for engagement with a brake band (not shown) of any desired type. Ribs or fins 19, preferably formed integral with the outer section 11 are connected between the peripheral portion 18 and the flange 13 thereof.

As previously stated, the flange portions of the sections are arranged in radial alinement, and are adapted to be connected by splice bars 20. These bars are preferably arranged in pairs on opposite sides of the flanges and are connected to the flanges of the respective sections by bolts or pins 21. It will be noted that the inner and outer pins

21 are staggered with relation to each other, for a purpose to be described.

The operation of the device is as follows:

5 Rotation is imparted to the inner section 10 by driving the shaft connected to the hub 14. This rotation is transmitted to the outer section 11 through the medium of the splice bars 20 as will be obvious, these elements forming rigid driving connections between the inner and outer sections.

15 As previously stated, the brake face of the rim 18 is subjected to the action of friction when the device is in operation, and accordingly becomes highly heated whereby it expands. At the same time, the inner section 10 remains comparatively cool, and thus is not subjected to the same degree of expansion. When an integral brake drum is put to the use for which the present device is intended, 20 the difference in the degree of expansion between the inner and outer portions of the drum sets up severe internal stresses which frequently cause the drums to break, thus resulting not only in damage to the parts 25 but also in injury to operators. With the present construction, the outer section 11 is adapted to freely expand and contract without affecting the inner section in any way, the splice bars 20 pivoting slightly about the 30 axes of the pin 21. Thus the positive driving connection is maintained, and the device operates efficiently without danger of damage or any injury to persons.

35 The pivot pins of the links or splice bars are offset radially from each other to permit the free differential expansion and contraction referred to. Obviously, if these pivot pins were arranged in radial alinement, there would be a direct pulling or compressing 40 force on the links, according to whether the outer section expanded or contracted. With the present construction, however, the expansion and contraction of the parts is unimpeded.

45 In the manufacture of the device, the adjacent faces of the flanges 12 and 13 may be made of substantially the same diameter with only sufficient clearance to permit the elements to be assembled. The matter of 50 the clearance between these elements, however is not important, and any desired clearance may be provided.

The fins 19 serve not only to provide effective reinforcing means between the rim 18 55 and its associated flange, but also act as radiating fins to assist in lowering the temperature of the outer section 11. In addition the fins also serve the function of agitating the air adjacent the drum, thus assisting in the 60 radiating action. This agitation of air also is assisted by the fins 17 which act as centrifugal fan blades to constantly feed air outwardly toward the outer section 11.

65 It is to be understood that the form of the invention herewith shown and described

is to be taken as a preferred example of the same and that various changes in the shape, size and arrangement of parts may be resorted to without departing from the spirit of the invention or the scope of the subjoined claims.

I claim:

1. A device of the character described comprising a pair of concentric rotatable elements, one of said elements being provided with a face adapted to be engaged by a friction element and adapted to partake of expansion and contraction independently of the other element, said elements being adapted to partake of limited relative rotation upon said expansion and contraction, and means for connecting said elements together to rotate as a unit.

70 75 80 85 90 95 100 105 110 115 120 125 130

2. A device of the character described comprising a pair of concentric inner and outer elements, said outer element having an annular rim provided with a face adapted to be engaged by a friction element, the outer of said elements being adapted to expand independently of the inner element, said elements being adapted to partake of limited relative rotation upon said expansion and means for connecting said elements together to rotate as a unit.

3. A device of the character described comprising a pair of correlated rotatable elements, one of said elements being provided with a face adapted to be engaged by a friction element and adapted to expand independently of the other element, and pivotally mounted connecting means arranged between said elements.

95 100 105 110 115 120 125 130

4. A device of the character described comprising a pair of concentric rotatable elements, one of said elements being provided with a face adapted to be engaged by a friction element and adapted to expand independently of the other element, and a link pivotally connected at its ends to said rotatable elements.

110 115 120 125 130

5. A device of the character described comprising a pair of concentric rotatable elements arranged one within the other, the outer element being provided with a rim having an annular face adapted to be engaged by a friction element and being adapted to expand independently of the other element, and a link pivotally connected at its ends to said rotatable elements.

120 125 130

6. A device of the character described comprising a pair of concentric rotatable elements arranged one within the other, the outer element being provided with a rim having an annular face adapted to be engaged by a friction element and being adapted to expand independently of the other element, and a link pivotally connected at its ends to said rotatable elements, the pivot points of said link being radially offset with respect to each other.

7. A device of the character described comprising a pair of concentric inner and outer elements each including a radial flange arranged in radial alinement with each other, said outer element having an annular rim provided with a face adapted to be engaged by a friction element, said outer element being adapted to expand independently of the inner element, a link arranged flat against said flanges, and pivot pins connecting the ends of said link to the respective flanges.

8. A device of the character described comprising a pair of concentric inner and outer elements each including a radial flange arranged in radial alinement with each other, said outer element having an annular rim provided with a face adapted to be engaged by a friction element, said outer element being adapted to expand independently of the inner element, a plurality of pairs of links arranged against opposite sides of said flanges, and pivot pins connecting the respective ends of said pairs of links to the respective flanges.

9. A device of the character described comprising a pair of concentric inner and outer elements each including a radial flange arranged in radial alinement with each other, said outer element having an annular rim provided with a face adapted to be engaged by a friction element, said outer element being adapted to expand independently of the inner element, a plurality of pairs of links arranged against opposite sides of said flanges, and pivot pins connecting the respective ends of said pairs of links to the respective flanges, the pivot pins of each pair of links being radially offset from each other.

In testimony whereof I affix my signature.
WILLIAM SCHWEMLEIN.
